UNITED STATES PATENT OFFICE.

ALEXANDER H. J. TJEENK WILLINK, OF MARTINEZ, CALIFORNIA.

FILING SYSTEM.

Application filed February 4, 1920. Serial No. 356,253.

To all whom it may concern:

Be it known that I, ALEXANDER H. J. TJEENK WILLINK, citizen of Holland, residing at Martinez, in the county of Contra Costa, State of California, have invented a new and useful Filing System, of which the following is a specification in such full and clear terms as will enable those skilled in the art to construct and use the same.

10 This invention relates to a filing system and method of filing cards, an object of which is to provide means whereby a missing card or a misplaced card of the series may be immediately located.

15 It will be understood by those familiar with alphabetical filing systems that when a card is misplaced it is necessary to hunt through practically all of the cards of the system and examine the data upon the cards 20 to find the missing card or to find the misplaced card, for sometimes the card is taken away and at other times it is simply misplaced.

With the present invention means is provided to ascertain first whether or not all of the cards or leaves in the filing system are in their proper initial alphabetical order, and second, whether all of the cards in their proper initial alphabetical order are in their 30 proper alphabetical order with respect to their second index letter or with respect to any additional data that it may be desired to place upon the cards for indexing them with respect to their particular position in the filing system, and third, to ascertain exactly what card or leaf of the series is missing, thereby enabling one to locate the data that particular sheet should contain.

Other objects of the invention will appear 40 as the description proceeds.

In the drawings in which the same reference numeral is applied to the same portion throughout the several views:

Figure 1 is a front view of a card numbered 1555 showing the manner of indexing it.

Figure 2 is a front elevation of four cards as they would appear when the card system is being examined to locate the missing card.

50 Figure 3 is a perspective view of a card file showing the appearance of the top of the file after a series of cards properly indexed have been placed therein.

Figure 4 is a perspective view of several 55 cards of the B class showing one misplaced card.

Figure 5 is a perspective view of several cards of the B class showing one card with the second letter of the series misplaced.

It will be understood by those skilled in the art that while the term "card index" is used herein that this system of filing is applicable to any sheets or cards where they are filed alphabetically and carry any desired data, and is especially intended to provide an adequate indexing for a filing system that is being continually increased in the number of cards it contains from time to time.

The numeral 1 indicates the card which has the letters of the alphabet arranged along its upper side as indicated at 2. Just under the letters of the alphabet in the series indicated at 2 is a similar series of letters of the alphabet as indicated at 3, while 75 at the beginning of the second line is space for the card number, in the present instance No. 1555.

Arranged along the left hand border of the card are numbers from 1 to 10 inclusive, 80 as indicated at 4. At the top of the right hand corner of the card is the word "Preceding" while at the bottom of the right hand corner is the word "Following." The card number 1555 is then repeated in the 85 middle of the right hand edge of the card as indicated at 5, and just under the word preceding as indicated at 6 is the number of the card next preceding the card 1555, while at the lower corner of the card over 90 the word following is the number of the following card as indicated at 7. When the card is originally indexed a notch is cut out of it as indicated at 8, in the present instance the letter B, and the second letter of 95 the name is punched out of the card in the lower series of letters 3.

Each card of the series is notched on the top corresponding with the letter of the space into which it is to go, for example, 100 those cards of the box A have the A cut out; the same system being followed throughout the entire alphabetic series.

At the same time the card may be given a number as in the present instance 1555, and 105 this number is repeated at the right hand end of the card, and when the card is placed in the file in its proper position the card preceding is examined and its number 4501, for example, is placed under the word Preceding, and the number 1675, for example, 110 of the card following is placed at the lower

right hand corner of the card over the word Following. Both the preceding card and following card then have their numbers adjusted accordingly and the system is complete for further inspection.

It will be apparent that if any card is misplaced from the series D and placed in the series B that such card will appear in the trough formed by notching all of the B 10 cards where the B occurs at their upper edges, as shown in Figure 4 where the letter B is seen in the notch of the front card and where its notch is seen just in back of the letter D. It will also be apparent that if a 15 card of the series B is merely misplaced in its own box, for example, if the next letter is A that it will be found with a hole to the left of holes in cards in front of it, and it will be apparent that the proper 20 order is for the holes in the series of letters 3 to proceed from left to right as the cards are examined from front to back so that by running over the cards the location of the holes will at once determine whether those 25 cards are in their proper position. If there are a plurality of cards containing first letters Ba, then the series of numbers 4 along the left hand edge of the card may be punched out and the proper position of those cards 30 in the series Ba will be determined similarly for the hole in the tenth card should be found below the holes in the front cards.

The foregoing designations enables one to 35 at once locate any card that is misplaced in the file, but assuming a card to be missing we can at once discover the missing card by picking up a bundle of cards and slipping them past one another until they stand in the position of the four cards shown in Figure 2, in which event if the card file is complete there will be a complete series of 40 numbers extending diagonally across the ends of the cards; for example, in Figure 2 there are two complete series of numbers 45 450 and 555, while there is an incomplete series of numbers 64—300—675 and 82, thus showing that the card 64 and the card 82 are both missing from the file. It will be apparent that following this system any 50 additional data may be similarly indexed should that be desired.

What I claim is as follows, but various

modifications may be made in the construction shown in the drawings and above particularly described form, within the pur- 55 view of my invention.

1. A filing system comprising a plurality of sheets carrying aligned notches in several different series to indicate the proper position of the sheet in the file, each sheet having a hole arranged therein in a non-aligned successive order to indicate the sub-position of the sheets in the file. 60

2. A filing system comprising a plurality of sheets, each sheet bearing an individual 65 number and the number of the preceding sheet and following sheet.

3. A filing system comprising a plurality of sheets, each bearing an individual number and carrying the number of the preceding sheet above the individual number and the number of the following sheet below the individual number. 70

4. A filing system comprising a plurality of sheets bearing a primary alphabet and a secondary alphabet, both alphabets arranged with their letters in succession, a notch in each sheet to indicate the position of the sheets in the file with respect to the primary alphabet, a hole in each sheet to indicate the sub-position of each sheet in a given series, and information upon each sheet to determine the loss of a sheet from the file. 75

5. A filing system comprising a plurality of sheets each provided with several serially arranged series of characters, each sheet having notches along one edge to indicate the position of the sheets in a filing system with respect to one of the series of characters, said sheets also having holes 80 through certain of the other characters on the sheet to indicate sub-positions of the sheet in the filing system. 85

6. A loose leaf filing system comprising a series of sheets, individual paging along 90 one edge of the several sheets to disclose the paging of the following and preceding sheets arranged adjacent the given page number on each sheet for detecting the loss of a sheet. 95

In testimony whereof I have hereunto set my hand this 28th day of January A. D. 1920.

ALEXANDER H. J. TJEENK WILLINK.
